UNITED STATES PATENT OFFICE.

EDGAR ROUSE SUTCLIFFE, OF LEIGH, ENGLAND, ASSIGNOR TO PURE COAL BRIQUETTES LIMITED, OF CARDIFF, WALES.

DISTILLATION OF CARBONACEOUS SUBSTANCES.

1,279,172.

Specification of Letters Patent. Patented Sept. 17, 1918.

Application filed April 12, 1915. Serial No. 20,923.

To all whom it may concern:

Be it known that I, EDGAR ROUSE SUTCLIFFE, a subject of the King of Great Britain and Ireland, residing at Leigh, Lancashire, England, have invented certain new and useful Improvements Relating to the Distillation of Carbonaceous Substances, of which the following is a specification.

This invention relates to a method for the distillation, gasification or coking of carbonaceous substances, and has generally for its object to effect the operation with economy and efficiency. The invention has especially for its object to effect the coking of solid blocks of coal or of substances having the character of coal from which blocks may be produced for the production of fuel by coking, or of blocks produced according to a process that broadly consists in the reduction of the carbonaceous raw material to a very fine state of division or flour and in then compressing this very finely divided substance into solid blocks or briquets under such conditions that the block or briquet may expand under the stresses imposed in its production so as to produce a solid and compacted block or briquet, which is then coked so as to produce a hard and dense coke capable of use for the various purposes for which coke as ordinarily made is applicable and generally for use as a fuel.

The blocks or briquets produced may be produced from finely divided coal without the use of a binder, while other bodies of the character of coal, namely, anthracite, coke and charcoal, may be used as the raw material, and by the incorporation with them of coal, pitch or other binder solid blocks may be produced on compression which by being heated in an oven may be coked for the production of a useful fuel applicable for the purposes for which anthracite, coke or charcoal is usually employed, as well as for other purposes according to the character of the raw material employed.

The present invention relates to a process of distillation, gasification or coking, which is of special utility in the production of a dense and hard coke of the character indicated when compressed blocks of coal or other carbonaceous substances are used in the manner described.

According to the invention I effect the distillation, gasification or coking by the internal application of heat, or partly by the

internal and partly by the external application of heat, to the oven and its charge, and I effect the distillation, gasification or coking in such manner that the gas destined for the internal heating of the charge next to be distilled, gasified or coked is first passed through one or more of the ovens in which the coking has been completed as far as required, so that the gas is thus heated before it is passed through the charge to be coked, and I admit a determined quantity of air into the oven or into the ovens in which the charge is to be distilled, gasified or coked, and I pass the gases and vapors evolved as the result of the distillation or gasification through another oven or through other ovens in which a fresh charge has been introduced, and by so doing, these fresh charges are heated and the gases cooled before the gases and vapors pass to the condenser. By such means it will be understood that the residual heat of the gases and of the charge is effectively utilized, whereby the process is carried out with considerable economy.

It will be understood that the invention is not limited to the employment of any particular number of ovens, nor yet to any particular number of ovens in which the same stage of the process is simultaneously carried out, nor is it limited to the series working of the ovens as it is possible for the gas destined for preheating the fresh charges to be passed in series or in parallel through a number of ovens, and in series or in parallel to be ignited or partially ignited in one or a number of ovens.

The invention comprises the system of ovens which is hereinafter described.

The invention is illustrated by way of example in the accompanying drawings, in which—

Figure 1 represents in diagrammatic sectional elevation a number of ovens in which the process can be carried out;

Fig. 2 is a diagrammatic plan corresponding to Fig. 1;

Fig. 3 is a diagrammatic section through two oppositely disposed ovens on the line *x—y* of Fig. 1;

Fig. 4 is a diagrammatic sectional plan through two oppositely disposed ovens on the line *v—w* of Fig. 1; and

Fig. 5 is a diagrammatic end elevation corresponding to Figs. 1 and 2,

Each of the ovens in the system illustrated in the accompanying drawings consists of a cylindrical casing *a* lined with firebrick and provided at its upper end with an aperture *b*, through which the charge is introduced into the oven and which is capable of being closed by means of a gastight cover. The bottom *c* of the oven may be formed of conical shape, and it is provided with an aperture, through which the contents of the oven may be discharged, which aperture may be closed by a valve or door *d*. Gas previously passed through or produced in another oven is led into the oven *a* through the pipe *e*, from a pipe *h*, the gas having first passed from the main gas supply pipe *j* through the branch pipe *l* into one or a number of the ovens in which it is pre-heated, thence passing through the pipe *e* into that oven in which it is to be burnt for effecting the distillation of the charge, while air may be admitted into the oven from the pipe *f*. The pipes *f* and *e* are connected to an outwardly extending part *g* formed at the upper part of the casing *a* of the oven. At the lower end of the oven a circular pipe *h* is disposed, which is connected with the oven by the radially disposed pipes *h*¹.

In the system of ovens illustrated in Figs. 1 and 3, twelve ovens are provided for successive working, and these are numbered 1 to 12 in the order in which the coking process may be effected in them, indicated by the arrows in Fig. 2. Three pipes *i*, *j* and *k*, common to the respective ovens, are laid between the series 1 to 6 and 7 to 12, as illustrated in Figs. 2, 3, 4 and 5. The pipe *i* serves to conduct air, which may be forced through by such means as a fan, and air is supplied to the respective ovens on each side through the pipes *f*. The common pipe *j* serves to carry the gas supply for heating the charge, and the gas passes from the pipe *j* to the respective ovens through the pipes *l*. The pipe *k* serves as the gas main into which the gaseous products of the distillation pass from the circular pipes *h* of the respective ovens, passing into the pipe *k* through the branches *h*², each of which is provided with a valve. Valves *f*¹, *l*¹ and *e*¹ serve to close or open communication through the respective pipes *f*, *l* and *e*, while the valves provided on the branch pipes *h*² serve to cut off communication from each oven with the gas main *k*. By such means it is possible completely to isolate each of the ovens, to pass gas or to pass gas and air into any oven or number of ovens so as thus to carry out the method of the invention.

60 A convenient way of working the system of ovens diagrammatically represented in the figures as indicated therein, where in the ovens Nos. 1 and 12 the coke produced is being emptied, while the oven No. 11 or ovens Nos. 2 and 11 are being charged with com-

pressed blocks of coal by means of a conveyor *m*. Oven No. 10 may be ready for treatment, having been filled with a fresh charge. Ovens Nos. 7, 8 and 9 may be undergoing preheating by means of gas discharged from the oven No. 6, in which a certain quantity of gas will have been burned, to effect the distillation of the charge in that oven, while ovens Nos. 3, 4 and 5 contain a charge that has been completely coked to the extent required and have gas passed through to be preheated before being passed into the oven No. 6.

It will be understood that the ovens Nos. 6 and 7 and 12 and 1 in the series represented in Figs. 1 and 2 are connected together and with the common pipes *i*, *j* and *k*, so that the cycle of operations can take place in succession through all the ovens in the series.

It will be understood that in the system of working described air is admitted only into the oven No. 6, where the actual process of distillation or gasification is for the time being carried out. The quantity of air admitted, however, is determined so that the combustion of the gas may as far as practicable take place in the upper part of the oven under conditions where little if any free oxygen passes through the charge.

When coking blocks of the kind hereinbefore described I prefer to provide a conveyor such as *m*, but I may charge as well as discharge the ovens from below in a manner and by means that are well understood, or I may provide rails passing beneath the respective ovens by which wagons may be brought immediately beneath them for receiving the coke on its discharge; or again, the charge may be received into a quenching tank or apparatus.

105 I prefer to provide means for the admission of steam into each of the ovens, by which sulfur and nitrogen may be driven off, or I may pass steam through the charge in the respective ovens under conditions where water-gas may be produced.

The products of distillation may be passed to a condenser and washing apparatus and be subject to treatment for the recovery of by-products, and the process may be carried out under a vacuum produced by the use of an exhauster, as is usual in the manufacture of gas.

110 Further, the air employed may be preheated, while combustion may be started by means of an oil spray, and the surplus gas not required for use in the process may be stored and used for any other purpose.

In the system of ovens illustrated in the accompanying drawings the process is carried into effect exclusively by internal heating, but it is obvious that the ovens may be heated externally as well as internally.

I claim:

1. A continuous method for the distilla- 130

tion of carbonaceous substances in a number of ovens by the internal application of heat, consisting in distilling the charges in said ovens in succession and in passing the gas required for supplying by its combustion the necessary heat for the distillation in one oven, first through another oven in which the distillation of the charge has already been effected to the extent required by which the 5
10 gas is thus heated on its passage through and is not consumed, passing the gas thus heated, with air into the first mentioned oven where a fresh charge is ready for distillation and effecting the combustion of such 15 heated gas therein for the distillation of its charge, substantially as described.

2.-A continuous method for the distillation of carbonaceous substances in a number of ovens by the internal application of heat, to 20 the charges therein; consisting in distilling the charges in said ovens in succession and in passing the gas and vapors produced on distillation of the carbonaceous substance in one oven directly through fresh charge of the 25 carbonaceous substance in another oven by which the said gases and vapors are cooled and part of the sensible heat of the gases or vapors is passed to the fresh charge, then admitting gas and air into the last mentioned oven to pass directly through the charge therein for effecting the distillation of the said charge, substantially as described.

3. A continuous method for the distillation of carbonaceous substances in a number 35 of ovens by the internal application of heat, consisting in passing the gas required for

supplying by its combustion the necessary heat for the distillation in one oven, first through another oven in which the distillation of the charge has already been effected 40 to the extent required, then passing the gas thus heated, with air into the first mentioned oven where a fresh charge is ready for distillation and effecting the combustion of such heated gas for the distillation 45 of the charge, and finally passing the gas and vapors produced on distillation of the said fresh charge through another oven containing a fresh charge of the carbonaceous substance by which the said gases and vapors are cooled and part of the sensible heat of the gases or vapors is passed to the 50 charge, substantially as described.

4. A method for the distillation of carbonaceous substances in a number of ovens 55 by the internal application of heat, consisting in successively heating the charge in the ovens by means of the vapors and gases produced on distillation of a charge in another oven, then admitting air together with 60 gas previously heated by passing through an oven in which the distillation has been effected to the degree required so that the said gas is pre-heated, then passing the pre-heated gas with air through the charge first referred to which has been pre-heated by the 65 vapors and gases from the distillation in another oven, substantially as described.
